UNITED STATES PATENT OFFICE.

ELMER E. MILLER, OF VALLEY VIEW, PENNSYLVANIA.

GAS-VALVE.

1,062,179.

Specification of Letters Patent. Patented May 20, 1913.

Application filed February 28, 1913. Serial No. 751,238.

To all whom it may concern:

Be it known that I, ELMER E. MILLER, a citizen of the United States, residing at Valley View, in the county of Schuylkill and State of Pennsylvania, have invented certain new and useful Improvements in Gas-Valves, of which the following is a specification.

This invention relates to improvements in gas valves and the object in the present invention is to provide a device in which provision is made for automatically closing the supply of gas to the burner, when the flame is accidentally extinguished.

15 The invention also includes means for taking up the wear on the valve plug, so as to insure a tight valve.

The invention further comprises a spring actuated valve and a thermostat provided 20 with means for releasing the spring action, so that when the heat of the flame is removed, by extinguishing the gas flame, the contraction of the thermostat will automatically release said spring action and permit it to close the valve, thus cutting off the 25 supply of gas to the burner.

The invention is more fully described in the following specification and clearly illustrated in the accompanying drawing, in 30 which:

Figure 1 is a front elevation of my invention. Fig. 2 is a fragmentary view, partly in section, taken through line 2-2 of Fig. 1.

The numeral 1 designates a gas supply 35 pipe and 2 an ordinary gas burner. Interposed between this burner and the end of the supply pipe 1, I place my valve, the casing 3 of which is attached to the screw-threaded end of the pipe 1, the casing being 40 provided at its top with a stem 4 for the burner 2. In the casing 3 I have shown a plug valve 5 whose rear or smaller end is formed with an annular depression 6, thus forming a head 7 on the extremity of the 45 plug.

The numeral 8 designates an adjusting device for taking up the play in the valve. This device comprises a bifurcated member 50 which fits loosely over the reduced portion of the plug, and bears against the under side of the head; one or both of its legs 8^a being bent inwardly and engaging the casing 3 by entering an indentation 9 therein, this will prevent relative rotation as between the member 8 and the casing. In the 55 top of the member 8 I place a set screw 10,

which when turned will bear against the surface of the casing 3 and exert a pressure against the head of the plug valve, tending to draw it tight in the casing and insure a 60 tight fit. On the stem 4 of the casing, I place a suitable bracket 15, formed with, or carrying, a thermostat, which thermostat 16 extends over the line of the burner flame. The free end 17 of this thermostat is provided with a latch having two stops or ledges thereon, 18 and 19. The forward end of the valve plug 5 is reduced in diameter, as shown at 20 and carries a pin 21 adapted to contact with a lug 22 on the face of the 70 casing 3 when the valve is closed and the supply of gas cut off. This reduced end of the plug valve is also provided with a loosely mounted sleeve 25 and its inner edge is cut away for a portion of its diameter, as shown 75 at 26, thus forming a contact point for engagement with the pin 21 when the sleeve rotates on the valve stem. This sleeve also carries an arm 30 whose free end is formed with an opening for engagement with the 80 free end of the thermostat, through the latch stops 18 and 19. A suitable spring 33 engages this arm, its opposite end being attached to a stationary point, shown in Fig. 1 as attached to an extension 40 of the thermostat bracket. This spring is normally in tension when the arm 30 is in engagement with the free end of the thermostat.

The operation of the device is as follows:—The plug valve is free to be turned 90 in either direction, that is to open or close it, without interfering with any of the other parts of the device. When the valve is open, and the gas ignited, the flame will expand the thermostat 16, and this will cause the 95 latch to disengage at the point 19, with the arm 30; the spring 33 will draw the arm down, but the latch will again engage the arm at the point 18 and will continue to hold it there as long as the flame burns, or 100 as long as the thermostat remains expanded. When, for any reason, the flame is extinguished, the thermostat will contract, release its hold on the arm 30, and the spring 33 will draw the arm down. As the arm 105 and the sleeve 25 to which it is attached, move around on the valve stem, the contact point 26 of the sleeve will meet the pin 21 on the stem and through this, will turn the valve and close off the supply of gas to the 110 burner. The movement of the valve is limited by the pin 21 contacting with the lug 22.

Having thus fully described my invention, what I claim and desire to secure by Letters Patent is:—

In a device of the character described the combination of a gas supply pipe, a burner, a thermostat provided with two latch points at its free end, a valve casing, a plug valve therefor, a pin carried by said valve, a sleeve loosely mounted on said valve and provided with a ledge for engaging said pin, and a

spring actuated arm carried by said sleeve, said arm having means at its free end for engaging the latch points on the free end of the thermostat.

In testimony whereof I affix my signature 15 in presence of two witnesses.

ELMER E. MILLER.
